UNITED STATES PATENT OFFICE.

DANIEL POWERS, OF PHILADELPHIA, PENNSYLVANIA.

LOCK.

Specification of Letters Patent No. 23,113, dated March 1, 1859.

To all whom it may concern:

Be it known that I, DANIEL POWERS, of the city and county of Philadelphia and State of Pennsylvania, have invented certain new and useful Improvements in Locks for Doors, &c.; and I do hereby declare and ascertain said improvements, referring to the accompanying drawing, in which—

Figures 1, 2 and 3 are plans of the lock with the inside plate removed; Fig. 4, same view with tumblers removed; Fig. 5, cross section of the lock.

My improvements consist principally in the expanding and contracting guards or fence which prevents the feeling out the proper position of the tumblers in attempting to pick the lock, or this expanding and contracting feature may be a part of the tumbler arrangement by reversing the construction without at all changing the principle.

The construction of the lock is substantially as follows: in which the figures shown in the drawing are described; the same references being used to designate like parts in all the drawings. The case *a* and bolt *b* are made like those of many locks now in use and there is a series of tumblers *t* to be properly raised by the key as in other tumbler locks. The bolt may be thrown by the revolving bit *e*, as seen in the drawing or it may be thrown by the bit of the key. I prefer the former arrangement where a series of loose stops are introduced into the revolving bit or center as shown at *s* Fig. 5, as they render the lock more difficult to pick but I omit more minute description of this

here as I now confine myself to the movable fence before named. On the bolt *b* I joint two pieces *f* between which the tumblers must stand when the bolt *b* is thrown back to unlock it, instead of these pieces or fence being permanently affixed to the bolt as in ordinary cases they are movable so as to have their ends which are toward the tumblers *t* approach toward or recede from each other. This approach is shown by red lines in Fig. 2, and the expansion in Fig. 3. The two are made to move together by the joint pieces *j* which connect them. Now it will be seen that if the tumblers are not properly raised so as to pass between the two bars *f* of the fence they will strike one or the other of them when the bolt starts back and immediately contract them so as to render it impossible for the tumblers to pass until the fence is restored again to place by again carrying the bolt forward. But if the tumblers are so raised they work entirely free between the parts. If this independent movement be connected with the tumblers instead of the fence the effect will be the same.

Having thus fully described my improved lock what I claim and desire to secure by Letters Patent is—

1. The independent movable expanding and contracting fence or its equivalent substantially as above set forth.
2. I also claim the union of the upper and lower halves thereof as herein specified.

D. POWERS.
